UNITED STATES PATENT OFFICE.

JAMES S. CROSSLEY, OF SYRACUSE, NEW YORK, ASSIGNOR TO PASS & SEYMOUR, INC.,
OF SOLVAY, NEW YORK, A CORPORATION OF NEW YORK.

ELECTRIC ROSETTE.

957,547.

Specification of Letters Patent. Patented May 10, 1910.

Application filed October 20, 1896. Serial No. 339,796.

To all whom it may concern:

Be it known that I, JAMES S. CROSSLEY, a citizen of the United States, residing at Syracuse, in the county of Onondaga and State 5 of New York, have invented new and useful Improvements in Electric Rosettes, of which the following is a specification.

My invention relates to rosettes for incandescent electric lighting and consists in a new form of that type of rosette, or ceiling block, which is provided with a recess to receive a knot in the conductors or lamp wires, whereby the weight of the lamp, or other device, is sustained.

15 This rosette is strong, light and compact.

My rosette consists of a one-piece body, or block, of porcelain, or other suitable insulating material, having secured on its lower surface opposite, metallic, wire terminals, 20 carrying at their outer ends binding screws for the line wire, and, at their inner ends binding screws for the lamp wires. Its characteristic features are a flat base and a small circular boss made hollow to provide 25 the knot recess: on each side of the open mouth of the recess, the walls of the boss are slightly undercut forming notches adjacent to the inner ends of the terminals to receive the short ends of the conductors extending 30 to the binding screws.

My invention is fully shown in the drawing herewith, in which the reference letters and numerals of the description indicate the corresponding parts in all the figures.

35 Figures 1 and 2 are respectively bottom plan and front elevation of my rosette. Fig. 3 is a side elevation. Fig. 4 is a section parallel to Fig. 3. Fig. 5 is a front elevation with the knot and the conductors in place.

40 In the figures, 1 indicates the flat base, having integral, opposite ears 2-2 for the terminals 3, and circular or disk-shaped, if desired, but preferably flattened on the front and rear edges to save material, space, etc.

45 Centrally on the base is arranged the circular boss 5, formed hollow to provide the recess 6 for the knot α ; from the recess extends the central hole 7 for the depending conduc-

tors b ; the wall 8 of the boss is cut away on each side of the mouth to the recess, forming 50 notches 9 to receive the upper ends $c-c$ of the conductors, which are stripped and connected to the terminals by the binding screws 10-10; 11-11 are the outer, or line-wire, binding screws and 12-12 are the screws 55 to secure the terminals to the base. The knot recess is formed partly in the base; 13 is a groove in the base forming part of the open mouth to the recess. The boss may be molded as a separate piece and secured to the base, 60 but preferably the entire porcelain body is molded as one piece. The tip of the boss may be tapered as shown. The notches 9 are cut back about to the outer edges of the terminals, that is not quite to the middle or 65 transverse axis of the boss, so as to leave plenty of material for strength in the boss walls, and to make the notches convenient in size and position for the conductor ends $c-c$.

Having thus described my invention, what 70 I claim as new and desire to secure by Letters Patent, is:—

1. In a rosette, a one piece porcelain body having a flat base and a hollow boss; said boss having a side opening for the passage 75 of the knot, side notches formed in its walls for the conductor ends, a recess centrally to seat the knot and a passage from said recess for the depending conductors.

2. In an electric rosette, a one piece body 80 of porcelain having a flat base and a hollow cylindrical boss, said base and boss being formed to provide a central knot recess and with a side opening in the boss and a base groove for the passage of the knot to the 85 recess and said boss having side notches formed in its walls for the conductor ends and a central lower passage from the recess for the depending conductors.

In testimony whereof I have signed my 90 name to this specification in the presence of two subscribing witnesses,

JAMES S. CROSSLEY.
